UNITED STATES PATENT OFFICE

ALFRED E. ISCHINGER, OF WYOMISSING, PENNSYLVANIA, ASSIGNOR TO BERKSHIRE KNITTING MILLS, OF WYOMISSING, PENNSYLVANIA, A CORPORATION OF PENNSYLVANIA

DESIGN FOR A STOCKING

Application filed April 10, 1929. Serial No. 30,837. Term of patent 14 years.

To all whom it may concern:

Be it known that I, ALFRED E. ISCHINGER, a citizen of the United States, residing at Wyomissing, in the county of Berks and State of Pennsylvania, have invented a certain new, original, and ornamental Design for Stocking, of which the following is a specification.

The drawing is a side elevation of a stocking embodying my design.

The essentials of the design are a series of spaced horizontal narrow bands, with intermediate bands of diamond shaped figures arranged end to end and forming irregular horizontal stripes, and additional diamond shaped figures associated in vertical alignment with certain of said several band diamonds forming spaced irregular vertical stripes.

What I claim is:

The ornamental design for a stocking, as shown and described.

In testimony whereof I affix my signature.

ALFRED E. ISCHINGER.
